(57) **CLAIM**

The ornamental design for a luminaire with a geodesic optic, as shown and described.

DESCRIPTION

FIG. 1 is a perspective view of a luminaire with a geodesic optic according to an embodiment of the present invention. FIG. 2 is a side elevation view of the luminaire with a geodesic optic of FIG. 1.

FIG. 3 is another side elevation view of the luminaire with a geodesic optic of FIG. 1.

FIG. 4 is another side elevation view of the luminaire with a geodesic optic of FIG. 1.

FIG. 5 is another side elevation view of the luminaire with a geodesic optic of FIG. 1.

FIG. 6 is a top plan view of the luminaire with a geodesic optic of FIG. 1; and,

FIG. 7 is a bottom plan view of the luminaire with a geodesic optic of FIG. 1.
